UNITED STATES PATENT OFFICE.

WILLIAM G. KEITH, OF CHICAGO, ILLINOIS, ASSIGNOR TO WELSBACH TRAFFIC SIGNAL COMPANY, OF PHILADELPHIA, PENNSYLVANIA, A CORPORATION OF DELAWARE.

DESIGN FOR A SIGNAL DEVICE.

Application filed September 17 1926. Serial No. 19,094. Term of patent 14 years.

To all whom it may concern:

Be it known that I, WILLIAM G. KEITH, a citizen of the United States, residing at Chicago, in the county of Cook and State of Illinois, have invented a new, original, and ornamental Design for a Signal Device, of which the following is a specification, reference being had to the accompanying drawing, forming a part thereof.

Figure 1 is a side elevational view of a signal device showing my new design; and Figure 2 is a front elevational view of the same.

I claim:

The ornamental design for a signal device substantially as shown.

WILLIAM G. KEITH.
